VALVE LIFTER

Jason S. Frye, Sacramento, Calif.

Application January 17, 1930. Serial No. 421,466

3 Claims. (Cl. 29—86.3)

This invention relates to tools used in connection with the valves of gas engines to enable the valve stems to be disassociated from their springs and the locking means thereof when it is desired to remove the valves for grinding or replacement.

In engines used on a certain make of automobile each valve spring is seated in a hollow cone-shaped cup, flexibly but permanently connected with which are the vertically split keepers, which at their lower ends normally engage a groove in the valve stem and then hold the cup against further downward movement. Raising of the cup automatically disengages the keepers from the groove but upon pulling the valve stem upwardly or again lowering the cup the keepers naturally tend to again seat themselves in the groove, thus preventing the removal of the valve.

It is therefore necessary before the valve can be removed to hold the keepers positively spread at their lower ends, while the valve stem is being pulled clear of the keepers, or vice versa.

At present there is no tool in existence, as far as I am aware, for both raising the cup and holding the keepers spread, and to provide such a tool by means of which both operations may be simultaneously and easily accomplished forms the major object of the present invention. The use of this tool therefore saves considerable time and the subsequent labor cost in removing or replacing valves having keepers of this type, and avoids the use of a screw-driver or similar crude expedient as is now employed in endeavoring to hold the keepers spread while removing the valve stems and which is very hard and awkward to accomplish owing to the close and almost inaccessible quarters in which the parts are disposed.

A further object of the invention is to produce a simple and inexpensive device and yet one which will be exceedingly effective for the purpose for which it is designed.

These objects I accomplish by means of such structure and relative arrangement of parts as will fully appear by a perusal of the following specification and claims.

In the drawing similar characters of reference indicate corresponding parts in the several views:

Fig. 1 is a sectional elevation of my improved tool head shown in connection with a manipulating or lifting device, and operating on a valve to enable the same to be removed.

Fig. 2 is an enlarged view of the device showing the functioning of the same to hold the keepers spread.

Fig. 3 is a similar view showing the device as

initially operating on the valve and cooperating parts to reposition the keepers in position.

Fig. 4 is a similar view illustrating the final step of repositioning the keepers.

Referring now more particularly to the characters of reference on the drawing, the numeral 1 denotes the body of the tool—a tubular member having an enlarged head 2 on the top provided with a recess adjacent its periphery to receive and support the rim of the hollow cone-shaped cup 3 which is slidable on the valve stem 4 and forms the seat for one end of the valve spring 5. Projecting into the cup are the vertically split opposed keepers 6, which are of hollow and substantially bell-shaped form, contracted on their lower ends as at 7 below the cup to closely engage the circumferential groove 8 formed about the stem toward its lower end. These keepers are permanently but loosely suspended from the top of the cup by lips 9 on top of the keepers which are bent outwardly to overhang the top of the cup; the flaring sides of the cup normally engaging the swell of the keepers above their contracted ends to wedgingly press such ends together and into engagement with the groove.

Slidable in the body below the head is a plunger 10 whose downward movement is limited by cooperating shoulders 11 on the plunger and body, and which is provided with a head 12 on its lower end to serve as a manipulating member as well as a stop limiting the upward movement of the plunger. Opposed fingers 13, tapered somewhat on their opposite sides toward their upper ends, project upwardly from and are formed with the plunger.

The body 1 is rigidly fixed on one end of a suitable lever or lifting device, being preferably mounted on the outer end of one arm of a standard valve lifting tool which consists essentially of a pair of crossed arms 14 pivoted together intermediate their ends. The arms at the ends to which the body is fixed are adapted to project between the valve stem and a rigid engine part below, so that while one arm engages and rests on said part the body may be pressingly engaged with the valve spring cup. Therefore on bringing the opposite ends of the arms together the body will be raised and the valve spring compressed, the cup and keepers being then raised above their normal level. The keepers are then suspended from the lips and their lower contracted ends automatically spread away from the groove 8. If an attempt is then made however to pull the valve stem upwardly or again lower the cup without positively holding the

keepers spread they will again automatically close of themselves and will reenter the groove. By the use of the plunger and its fingers however this is avoided and the keepers are positively held spread, as will now be shown. To accomplish this end the plunger, after the cup and keepers have been raised as above stated, is then turned and raised until the fingers 13 project between the separated keepers, which position can be easily obtained by the feel of the plunger as it is turned, and the valve stem may be then easily drawn upwardly, or the spring and cup removed by lowering the tool while maintaining the plunger in its relatively raised position.

10 When replacing the valve it is sometimes only necessary to lift the cup so that the keepers are slightly above the level of the stem groove; and upon then lowering the tool the action of the cup on the keepers as the cup is released will tend to cause the keepers to be moved toward each other and into engagement with the stem groove. To make this action positive however the plunger may be manipulated so that the fingers 13 are moved to engage the lower ends of the keepers 25 midway between the split, as shown in Fig. 3, and by then lowering the tool while holding the plunger tight against the keepers the latter are positively guided into position in the stem groove as shown in Fig. 4, without the possibility of one 30 of the keepers moving down more than the other. The plunger may then be dropped and the tool removed.

From the foregoing description it will be readily seen that I have produced such a device as substantially fulfills the objects of the invention as set forth herein.

While this specification sets forth in detail the present and preferred construction of the device, still in practice such deviations from such detail 40 may be resorted to as do not form a departure from the spirit of the invention, as defined by the appended claims.

Having thus described my invention what I claim as new and useful and desire to secure by 45 Letters Patent is:

1. A lifter for a valve having a hollow spring seating cup slidable thereon, and vertically split keepers to surround the stem of the valve projecting into and loosely suspended from the top of the cup, said keepers at their lower ends being contracted and adapted to closely engage a circumferential groove in the stem with the pressure of the cup against the keepers; said lifter comprising a body adapted to be engaged with the cup to lift the same, lifting means associated with the body, a plunger slidably and turnably mounted in the body below the cup engaging portion thereof, and diametrically opposed fingers projecting upwardly from the plunger to pass between the keepers after the latter have been once separated by the raising of the cup. 80 85 90

2. A lifter for a valve having a hollow spring seating cup slidable thereon, and vertically split keepers to surround the stem of the valve projecting into and loosely suspended from the top of the cup, said keepers at their lower ends being contracted and adapted to closely engage a circumferential groove in the stem with the pressure of the cup against the keepers; said lifter comprising a body adapted to be engaged with the cup to lift the same so that the keepers may be substantially aligned with the stem groove, lifting means associated with the body, and a plunger slidably in the body below the cup engaging portion thereof to be engaged at will 100 105 with the keepers to hold the same against movement longitudinally of the stem while the cup is lowered about the keepers. 100 105

3. A valve-spring lifter comprising a body, adapted for connection to a lifting means, a circumferentially recessed head on the upper end of the body to engage the valve-spring cup, a plunger slidably in the body and projecting upwardly toward the head, and opposed fingers projecting upwardly from said plunger to project 110 115 120 between the valve-stem keepers. 110 115
